DESIGN FOR A HARMONICA

Charles H. Bennington and Irving L. Stein, New York, N. Y., assignors to Harmatone Company, Inc., New York, N. Y., a corporation of New York

Application January 8, 1934, Serial No. 50,354

Term of patent 14 years

To all whom it may concern:

Be it known that we, CHARLES H. BENNINGTON and IRVING L. STEIN, both citizens of the United States and residents of New York, in the city, county, and State of New York, have invented a new, original and ornamental Design for a Harmonica, of which the following is a specification, reference being had to accompanying drawing, forming a part thereof in which

Figure 1 is a perspective view of a harmonica showing my new design;

Fig. 2 is a longitudinal elevation thereof and Fig. 3 is an end view of such harmonica.

We claim:—

The ornamental design for a harmonica, as shown.

Signed at New York, in the city, county and State of New York, this 19 day of December, 1933.

CHARLES H. BENNINGTON.
IRVING L. STEIN.
